(57) **CLAIM**

The ornamental design for an automobile panel mesh or replica thereof, as shown and described.

DESCRIPTION

FIG. 1 is a left elevation view of an embodiment of an automobile panel mesh or replica thereof in accordance with the present design;

FIG. 2 is a front, left perspective view thereof;

FIG. 3 is a right elevation view thereof;

FIG. 4 is a front elevation view thereof;

FIG. 5 is a rear elevation view thereof; and,

FIG. 6 is a top plan view thereof.

The broken line showing of the motor vehicle or replica thereof is provided for the purpose of illustrating environmental structure and forms no part of the claimed design. The dot-dash lines in the drawings are provided to indicate the boundaries of the claimed design.

1 Claim, 6 Drawing Sheets
